UNITED STATES PATENT OFFICE

146,688

DESIGN FOR A HANDLE FOR COFFEE POTS
OR THE LIKELeland H. Snyder, Chicago, Ill., assignor, by mesne assignments, to Quality Appliances, Inc.,
Chicago, Ill., a corporation of Illinois

Application February 8, 1946, Serial No. 126,385

Term of patent 14 years

(Cl. D44—26)

To all whom it may concern:

Be it known that I, Leland H. Snyder, a citizen of the United States and a resident of the city of Chicago, in the county of Cook and State of Illinois, have invented a new, original, and ornamental Design for a Handle for Coffee Pots or the like, of which the following is a specification, reference being had to the accompanying drawing, forming a part thereof.

On the drawing:

Figure 1 is a perspective view of the handle for coffee pots or the like, showing my new design, and

I claim:

The ornamental design for a handle for coffee pots or the like, as shown.

LELAND H. SNYDER.
